PATENTED APR. 24, 1906.

C. F. LAUR.
VARIABLE SPEED MECHANISM.
APPLICATION FILED JAN. 5, 1906.

UNITED STATES PATENT OFFICE.

CHARLES F. LAUR, OF CINCINNATI, OHIO, ASSIGNOR TO THE LODGE & SHIPLEY MACHINE TOOL COMPANY, OF CINCINNATI, OHIO, A CORPORATION.

VARIABLE-SPEED MECHANISM.

No. 818,632.

Specification of Letters Patent.

Patented April 24, 1906.

Application filed January 5, 1906. Serial No. 294,770.

To all whom it may concern:

Be it known that I, CHARLES F. LAUR, a citizen of the United States, residing at Cincinnati, in the county of Hamilton and State 5 of Ohio, have invented certain new and useful Improvements in Variable-Speed Mechanism, of which the following is a specification.

My invention relates to a variable-speed 10 device which is primarily adapted to constitute a train of gearing between the lead-screw and spindle of an engine-lathe. It is, however, adapted for either speed or feed purposes.

15 The object of the invention and the various features of the invention will be more fully set forth in the description of the accompanying drawing, forming a part of this specification, in which the figure shows a 20 metrical section representing the plan of gearing with reference to the various shafts of an engine-lathe.

1 represents, say, the spindle, on which is fixed the pinion 2.

25 3 4 5 6 represent a train of gears from pinion 2 on the spindle, transmitting motion to the gear 7 on shaft 8, which I will denominate a "tumbler-shaft."

9 represents a pinion adapted to turn with 30 and slide on shaft 8. Pinion 9 meshes with the tumbler-gear 10, which rocks on shaft 8 of the spindle. I have not shown the tumbler or lever by which this sliding and rocking is accomplished, for it is a well-understood 35 device. It is sufficient to say that such a tumbler is employed by means of which the gear 10 may be brought selectively into mesh with the cone of gears 11 12 13 14 15, fixed on shaft 16, which latter shaft I will denominate the "cone-shaft."

40 17 18 represent compound gears on the end of the shaft 16.

19 represents a stud carrying compound gears 20 21, gear 20 meshing with gear 18.

45 22 23 represent another compound gear on the stud-shaft 19, gear 23 meshing with gear 17. The gear 20 is always in mesh with the gear 18.

24 represents a gear adapted to turn with 50 and slide on the shaft 25, which I will denominate the "lead-screw."

The gears on the stud and said stud are rocked by tumbler mechanism (not shown)

on shaft 16 as a center, the gear 24 being 55 slideable to position to be engaged by any one of the gears 20 21 22 23.

If it be assumed that gear 7 is fixed on its shaft and gears 17 and 18 on their shaft, it will be readily understood that through the selective operation of the cone and tumbler 60 gears on shafts 8 and 16 five different speeds may be transmitted to the shaft 16 and that by rocking the stud 19 on shaft 16 as a center and by sliding the gear-wheel 24 on the shaft 25 the five different speeds of the shaft 16 65 may be multiplied by four, so as to give twenty ultimate speeds to the lead-screw. In fact, this plan so far described represents the conventional lathe as manufactured by The Lodge & Shipley Machine Tool Company, of Cincinnati, Ohio. In this plan, as 70 described, it is obvious that the motion flows directly from shaft 8 to shaft 16, and as to the lead-screw 25 the values of the ultimate speeds being determinable from the ratios of 75 the gearing when connected in the train, as just described. For a domestic lathe this arrangement is satisfactory; but in order to get the speed values demanded by a metric lathe for foreign uses it is necessary that the 80 driving relation of the cone and tumbler shafts be transposed, so that the motion flows from the spindle 1 directly down to the cone-shaft 16, then back to the tumbler-shaft 8, and thence down through transmitting- 85 gears to the lead-screw 25. It is obvious that by this line of drive the ratio of the gearing is completely inverted and that twenty speeds of different value are given to 90 the lead-screw. It will of course be understood that the lathe structure supporting this plan of gearing is an expensive item, involving its casting and their relative arrangement and their accommodation for the various gears in various set positions and involv- 95 ing various slotted plates and indexes, which not only house the gearing, but which are variously slotted or otherwise constructed to permit of certain fixed lines of movement of the levers for controlling the positions of the 100 gears. It is the prime object of my invention to provide means whereby the lathe structure containing the plan of gears, as above described, in which the tumbler-shaft drives the cone-shaft, may be retained intact 105 and yet utilized to support a plan of gearing

in which the cone-shaft drives the tumbler-shaft, and thus giving possible metric or other desirable results. By so doing it is obvious that the same working drawings, patterns, and structural parts may be utilized for either results, the assembling being practically identical and involving an immense saving of time and expense over any system which would not retain these conventional structures and devices.

Now to describe the plan in which the cone-shaft drives the tumbler, let it be assumed that the gear 7 is loose on shaft 8 and that it meshes with the gear 26, fixed to the cone-shaft 16. Thus it is obvious that the cone-shaft 16 will drive the tumbler-shaft 8. On the outer end of this tumbler-shaft 8 is a gear 27, which, assume, is fixed to the shaft 8, and which gear 27 meshes into the gear 18, and assume that the gears 17 18 are loose on the cone-shaft 16. It is obvious that motion flows from the spindle through gear-wheels 7, loose on shaft 8, to gear-wheel 26, fast on shaft 16, thence, say, through gears 11 10 9, the latter being fixed on shaft 8, to said shaft, thence through gear 27, fixed on shaft 8, to compound gears 17 18, loose on shaft 16, and thence through a selected gear of the group 20 21 22 23 to gear 24 on lead-screw 25. Thus it is obvious that the structures, grouping of shafts, and gear-trains, the same kind of variable-speed devices, and the same organization is employed for both forms.

It may be desirable in some instances, such as to give various pitches for various worm devices, to make the lathe with all of the gears precisely as described, but providing a device for converting the lathe into either style—that is, permitting the cone-shaft to drive the tumbler-shaft or the transposition of this driving relationship, which would obviously give two feed systems of different value. This result is also accomplished without in any wise disturbing the conventional structure and arrangement, which I desire to retain. To accomplish this result, I provide on the opposing faces of gears 27 and 7 the clutch members 28 and 29, respectively, and on shaft 8 I provide the double-face clutch member 30, coöperating selectively with the clutches 28 29 to fix either gear 27 or 7 to shaft 8, so that where one is fixed the other is essentially loose on the shaft. On the opposing faces of the gears 21 and 26 I place clutch members 31 32, which by means of the double clutch member 33 on shaft 16 may cause the gear 26 to be fast or loose on shaft 16 or may cause the gears 17 18 to be fast or loose on shaft 16. To the frame I fulcrum a lever 34 between the shafts 8 and 16, one end of which is attached to the double clutch 30 on shaft 8 and the other end of which is attached to the double clutch 33 on shaft 16. Thus it is ob-

vious that when the lever 33 is thrown to engage clutch members 28 30 the clutch 33 will engage clutch member 32, fixing gears 27 and 26 to their shafts, and the drive will be from the cone-shaft to the tumbler to get metric results. When the position of this lever 33 is reversed, gear 7 will be fixed to shaft 8 and gears 17 18 fixed to shaft 16, the drive being from the tumbler to the cone shaft. This transposition of the driving relationship of two shafts connected by differential gearing may be obviously utilized in the arts.

Having described my invention, I claim—

1. In a variable-speed device, a first, second and third shaft, a cone-and-tumbler gear system between the first and second shaft, a cone-and-tumbler gear system between the second and third shaft, a gear-wheel loose on the first shaft, means for rotating said gear-wheel, a fixed gear-wheel on the second shaft meshing with the said loose gear-wheel on the first shaft, the prime gear element of the cone-and-tumbler gear system, between the second and third shafts, being loose on the second shaft, and a fixed gear-wheel upon the first shaft intermeshing with the said prime change-gear element on the second shaft, substantially as described.

2. In a variable-speed device, a first, second and third shaft, a cone-and-tumbler gear system connecting the first shaft to the second, a cone-and-tumbler gear system connecting the second shaft to the third, loose gears on the first and second shafts, and clutch mechanism whereby the driving relationship of the first two shafts may be transposed, substantially as described.

3. In a variable-speed device, a first, second and third shaft, a variable-speed gear system between the first and second shaft, a variable-speed gear system between the second and third shaft, loose gears on the first and second shafts, and clutch mechanism whereby the driving relationship of the first two shafts may be transposed, substantially as described.

4. In a device of the class described, a first and a second shaft, gearing connecting said shafts, a pair of loose gears on the first shaft and an opposing pair of intermeshing gears loose on the second shaft, and means for clutching the diametrically-opposed gears to their respective shafts, whereby the driving relationship of said shafts may be transposed, substantially as described.

5. In a device of the class described, a first and a second shaft, gearing connecting said shafts, a pair of loose gears on the first shaft and an opposing pair of intermeshing gears loose on the second shaft, clutch members on the meeting faces of said gears, a double-faced sliding clutch keyed to each of said shafts between said clutch members, a lever

fulcrumed between said shafts and connected at opposite ends to said sliding clutch members, whereby the diametrically-opposed gears on the two shafts may be alternately fixed to their respective shafts transposing the driving relationship of said shafts, substantially as described.

In testimony whereof I have hereunto set my hand.

CHARLES F. LAUR.
